UNITED STATES PATENT OFFICE.

ELEANOR L. BAINBRIDGE-BELL, OF MOUNT BETHEL, PENNSYLVANIA.

SANITARY SHIELD.

1,138,440.

Specification of Letters Patent.

Patented May 4, 1915.

Application filed November 9, 1914. Serial No. 871,028.

To all whom it may concern:

Be it known that I, ELEANOR L. BAINBRIDGE-BELL, a citizen of the United States, and a resident of Mount Bethel, in the county of Northampton and State of Pennsylvania, have invented certain new and useful Improvements in Sanitary Shields, of which the following is a specification.

My invention relates to sanitary shields for the seats of water closets, and one of the main objects thereof is to provide such devices in the form of sheets of paper, preferably medicated, having protecting curtains connected therewith when in use, but which present no loose or flapping members before use.

A further object is to provide such shields which are cut, scored, perforated, or otherwise constructed along certain definite lines to permit ready separation of the material thereof along such lines by the weight of a person, said curtains being normally held in the plane of the shield by means of integral stays, when the material is cut along the lines, as shown in the drawings.

A further object is to so cut, score, or perforate the sheet of material that a front, a back, and opposite side curtains will result when the material is separated on the predetermined lines by a person seating himself thereon, after it has been placed upon a closet seat.

A further object is to so locate the cuts, score, or perforations, as not to interfere with the folding of the shield into a compact form for merchandising; and further objects are to provide such devices which are simple in construction and use, well adapted for the purpose for which they are designed, entirely protecting against contact between the skin of a person and the closet seat, and so low in cost as to make their use inexcusable.

My invention is fully described in the following specification, of which the accompanying drawings form a part, in which the separate parts are designated by the same reference characters in each of the views, and in which:—

Figure 1 is a plan view of a sheet of suitable material constructed in accordance with my invention; Fig. 2 is a view thereof with the stays broken and the curtains dependent, previous to receiving the weight of a person; and Fig. 3 is a view of the shield folded in such form as to be offered for sale.

In the drawings forming a part of this application I have shown a present preferred form of embodiment of my invention, comprising a sheet of suitable material 4 of rectangular shape, and which is adapted to be folded upon the centrally arranged longitudinal and transverse dotted lines shown in Figs. 1 and 2 when manufactured, for compact storage and ready for sale, there being no indication of the intended use when so folded. The sheet 4 is cut along a substantially semi-circular line, as shown at 7, in the front, and 8 in the rear, stays 9 and 10 being provided, however, for the respective curtains 11 and 12 so formed in order to maintain the curtains in the plane of the sheet until used; these semi-circular or segmental cuts 7 and 8 are terminated upon an imaginary line 13 following the line of the opening in the seat, whereby the material of the sheet remains intact over the surface of the seat, this being clearly illustrated. Arranged centrally and longitudinally of the sheet 4, between the segmental cuts 7 and 8, is a straight cut 14 not joining the said cuts 7 and 8, and thus not destroying the stays 9 and 10, this line cut, in conjunction with the segmental cuts 7 and 8, forming side curtains 15 and 16 joined, before use, by a stay 17 intercepting the line cut 14, and it will be seen that all four curtains remain in the plane of the sheet 4 up to the time of actual use.

In practice, a separate sheet is used by each person using the closet, being placed over the seat and, if desired, the stays 9, 10, and 17 may be manually torn to allow the curtains 11, 12, 15 and 16 to drop into the positions shown in Fig. 2, and, when the user seats himself, the curtains are forced into conformity with the contacting portion of the body of the user, the side curtains only being so affected, and the front and rear curtains, not being in direct contact with the body of the user, remain in the dependent positions shown in Fig. 2, and positively operate to prevent any contact of the person of the user with the bowl of the closet, and all of said curtains prevent such contact with the seat.

It will thus be seen that a thoroughly sanitary shield results, for the purpose stated, which requires only to be placed upon a closet seat in its vended form, the weight of the user forcing a plurality of protecting curtains into operative positions;

which is negligible in original cost but a positive factor in the prevention of contagion or inoculation in closets, being of the greatest importance in public comforts; 5 which is of such slight bulk and weight as to enable a person to carry a number thereof in pockets, hand-bags, or the like, ready for use; which may be, and preferably will be, medicated so as to positively counteract any 10 deleterious influences encountered; and which is of such form, when folded, as to be readily dispensed by coin-actuated machines, or vended in envelops in stores, news-stands, boats, stations, and in closets generally. I am aware that shields for this purpose have heretofore been designed, but they require that a section be manually torn out before use, thereby forming an opening which may be larger than the opening in a 15 closet seat, and thus render the device inoperative, or which shield opening may not register with the seat opening when a person seats himself because of the probable shifting thereof on a closet seat while the person is seating himself, and in which event the 20 shield is useless for its intended purpose; my shield, however, by the formation of dependent curtains all around the seat opening, can not be placed upon a seat without 25

being positively operative when a person 30 seats himself, or, if the curtains are previously forced down, said curtains form a guide for the position of the shield.

Having fully described my invention, what I claim as new, and desire to secure 35 by Letters Patent, is:

As an article of manufacture, a sanitary shield comprising a sheet of suitable material weakened adjacent one end on two quadrant lines jointly forming a broken 40 semi-circle curved toward the center of said sheet; similarly weakened adjacent the other end on quadrant lines jointly forming a broken semi-circle curved toward the center of said sheet, and weakened on a median 45 line from a point adjacent one semi-circular line to a point adjacent the center of the sheet, and similarly weakened on a median line from a point adjacent the other semi-circular line to a point adjacent the center 50 of the sheet.

In testimony whereof I have signed my name to this specification in the presence of two subscribing witnesses.

ELEANOR L. BAINBRIDGE-BELL.
